UNITED STATES PATENT OFFICE

JOSEPH M. BARRETT, OF FOSTORIA, OHIO, ASSIGNOR TO THE SWARTWOUT COMPANY,
OF CLEVELAND, OHIO, A CORPORATION OF OHIO

BOILER FEED WATER CONTROL SYSTEM

Application filed May 4, 1925. Serial No. 27,736.

This invention relates to the automatic control of boilers in power plants and is concerned more particularly with the automatic control of feed water to the boilers.

The rapid development of prime movers in large power units has necessitated a corresponding development in boiler equipment and auxiliary apparatus therefor. Such developments have presented the problem of obtaining an accurate boiler feed water regulation which will conform to the boiler rating demands and not solely upon changes in boiler water levels. A plurality of boilers, to be efficiently operated when serving a single header involves a great many considerations and an ideal apparatus for the purpose is one which will function to feed the water to the boiler in direct proportion to the steam delivery thereof, regardless of the variations in the steam delivery. Since such changes in the steam delivery, are dependent upon many conditions, the most important of which are changes in furnace heat conditions, variable steam demands on the boiler and variation in feed water temperature and delivery to the boiler, the one variable condition favorable to a proper feed water regulation is a variation in the boiler drum pressure and nozzle or header pressure.

The general object therefore of my present invention is to provide a pressure generator system for controlling the boiler feed line which is dependent primarily for its refinement in operation upon the variation in the rate of steam flow from the boiler.

In other words, my invention proposes the use of a pressure generator system which is directed to maintaining a practically constant water level in the boiler while being responsive to variations in the boiler rating or boiler demand. Wherefore I propose a particular arrangement of apparatus involving a novel method of feed water regulation including a pressure generator water regulating system which is directly responsive to variations in the difference of steam pressure in the boiler and the pressure in the boiler nozzle or steam line being serviced by the boiler.

Further objects of my invention will here-

inafter become apparent from the following description referring to the accompanying drawing which illustrates a preferred embodiment for carrying out my method of feed water regulation. The essential characteristics are summarized in the claims. 55

The drawing is an elevation view of a pressure generator, feed water regulating system arranged diagrammatically on the drum of a boiler. I show a drum 10 of a high rating water tube boiler provided with a feed water line 12 which is served by a pump 13, the latter being connected to a source of water supply such as a hot well. The pump 13 may be driven by any suitable power means such as a motor 15 mounted on the base thereof. The feed water line 12 is provided with a diaphragm operated valve mechanism 18 which is controlled by a pressure generator shown at 19 as being mounted upon a looped conduit or tube 20. The loop 20 may be connected to the boiler above and below the normal water level thereof through valve members 21 and 22 which are connected to branches extending from water column leads 23. The generator 19 is connected to the valve mechanism 18 through a conduit 24 and the general construction and mode of operation of the pressure generator and valve mechanism controlled thereby may be substantially as disclosed in the patent to Copley, No. 1,193,125 issued August 1, 1916. 70 75 80

As shown, the pressure generator 19 is disposed at the end of the boiler drum 10 in a position to span or extend through the normal plane of the water level in the boiler whereby variations in the water level will control the height or position of the steam in the conduit 20 and thus control the flow of feed water to the boiler by reason of pressure reactions on the diaphragm of the valve 18. 85 90

At 30, I show a pressure reducing valve mechanism which is connected to the boiler drum 10, through a conduit 32 communicating with the boiler below the normal water level thereof, and, as shown, this conduit may be connected to a drop branch extending from the lower part of the loop 20 of the pressure generator controlling the feed water flow. 95 100

valve 18. The prevailing boiler pressure in the drum 10 is exerted upon the upper face of the diaphragm 35 of the pressure reducing valve through the conduit 32, thus controlling the extent of the opening of the valve apertures 36.

An adjustable spring 37 may be set whereby the combined spring pressure and prevailing boiler pressure will determine the extent of pressure in the feed water line 12. This mechanism is described and claimed in my copending application filed concurrently herewith and the purpose of such mechanism is to maintain in the feed water line 12 and particularly at the flow regulating valve 18, a constant excess pressure over the prevailing boiler pressure while the pump 13 maintains the pressure in the part 12a in the feed water line under all conditions in excess of the maximum pressure which may occur in the boiler drum 10.

The operation of the feed water flow regulating valve mechanism 18 by the pressure generator 19 under certain conditions is not sufficiently responsive to changing water level conditions in the boiler, (particularly when these changes are to prevent boiler rating changes) either an overfeeding or an underfeeding of the boiler and this sluggish operation is characteristic of all devices adapted to the regulation of feed water flow and which are responsive only to variations in the water level in the boiler. I accordingly provide an additional means in the form of an auxiliary pressure generator system, which in its operation is entirely independent of the water level condition of the boiler and which is responsive to variations in the steam demands made upon the boiler. Such variations in the steam demand upon the boiler, sets up a variable or differential in the prevailing pressure within the boiler and the pressure in the boiler nozzle 10a for the reason that the flow of steam is only occasioned by there being a greater pressure at the source than at the outlet or any place intermediate thereto and I utilize this characteristic for feed water control by connecting a manometer tube to the boiler drum above the water level thereof and to the boiler nozzle 10a and it may be of such length as to carry a water column having a hydrostatic head equal in pressure to the maximum difference in pressures which may exist between the boiler drum and boiler nozzle. This tube, as shown in the drawing comprises a downwardly extending conduit 40 which is connected to an upwardly extending stretch of pipe 41 terminating in a head reservoir 42. The length of the tube loop and the capacity of the reservoir 42 is such that a head pressure will prevail in the upwardly extending stretch 41 of the conduit which will balance the excess pressure prevailing in the boiler drum over the nozzle pressure and I

arrange upon the downwardly extending conduit section 40, a pressure generator or a plurality of pressure generators 45 connected by conduits 46 to each other and to the diaphragm of the feed water flow valve mechanism through a conduit 47. When the pressure in the drum 10 increases, an increase in the difference between the pressures in the drum and the nozzle 10a will cause a depression of the liquid column in the conduit 40; thus permitting the steam in the boiler drum to reach the top one of the pressure generators 45 and as this difference is further increased, consequent to further increases in the boiler pressure or rating demand, the steam in the conduit 40 will reach the remaining pressure generators and this additional pressure serves to cooperate with the pressure generator 19 in regulating the valve mechanism 18. Sudden decrease in the boiler rating demand, in other words a checking of the fire and a resulting drop in the boiler pressure permits the counterbalancing hydrostatic pressure caused by the pressure head reservoir 42 and column 41, to cause the liquid in the column to flow upwardly in the conduit 40.

It will be seen that this auxiliary system is to be placed in operation only after a certain pressure prevails in the boiler when the latter is being placed in service and I accordingly provide a valve 50 in the loop which will prevent the liquid supply in the head reservoir 42 from escaping from the loop, and if for any reason it is desired to depend upon the regulation afforded by the pressure generator 19, the auxiliary system may be rendered inactive by closing the valve 50.

From the foregoing description of my invention it will be seen that I obtain a double regulation of the boiler water level and that my system is particularly adaptable for use in high pressure, high rated boilers having a comparatively small water space; that I first control the pressure in the feed water line whereby it will remain at a constant excess over the prevailing boiler pressure regardless of variations in the boiler pressure and then I obtain a refinement in the control of the feed water valve by a pressure generator system which is dependent for its operation upon variations in the differences in prevailing boiler drum pressure and nozzle pressure thus giving a very refined regulation in the feed water flow to the boiler, which regulation is dependent upon or in direct proportion to changes in the boiler rating demand. It will be also noted that the characteristics of my system of regulating boiler feed water are such that the control valve may be installed at any point either above or below the boiler drum.

Having thus described my invention, I claim:

1. In a feed water regulating system for a boiler, the combination of a feed water line,

a diaphragm valve controlling said line, a pressure generator means having a connection above and below the normal water level of the boiler, a conduit extending between said means and said valve whereby variations in pressure in said generator consequent to varying water levels in the boiler will vary the condition of the valve, a conduit connected to the boiler drum above the water level thereof and having a liquid therein and to a nozzle or steam line leading from the boiler, and a pressure generator mounted on said conduit and also connected to said valve.

2. In a feed water regulating system for a boiler system, the combination of a pressure operated valve controlling the feed water line of the boiler, pressure generator means attached to the boiler and connected to the valve to operate the same, and a second pressure generator means comprising a closed loop having the ends thereof connected to the boiler and to a line leading therefrom with an outlet thereof above the normal water level of the boiler, and having a liquid therein, said pressure generator means being connected to said valve to operate the same.

3. In a feed water regulating system for a boiler, the combination of a feed water line, a pressure operated means responsive to varying water levels in the boiler for controlling the feed water line, a conduit containing liquid and connected to the boiler drum above the water level thereof and to the boiler nozzle or steam line leading from the boiler, and a pressure generator mounted on said conduit and connected to said feed water controller to operate the same in response to variations in the steam demand on the boiler.

4. In a feed water regulating system for a boiler, the combination of a pressure operated valve controlling the feed water line of the boiler, pressure generator means attached to the boiler and connected to the valve to operate the same, and a second pressure generator means containing liquid having a connection to the boiler above the normal water level of the boiler, and to the boiler nozzle or line serviced by the boiler and means connecting said pressure generator means to said valve to operate the same in cooperation with the first named pressure generator means.

5. In a feed water regulating system for a boiler, the combination of a feed water line, a diaphragm operated valve controlling said line, a pressure generator means having a connection above and below the normal water level in the boiler, a conduit extending between said means and said valve whereby variations in pressure in said generator consequent to variations in the elevation of the boiler water level will vary the condition of the valve by operating the diaphragm, a conduit in the form of a depending loop containing liquid connected to the boiler drum above the water level thereof and to a steam noz-

zle leading from the boiler, a pressure generator mounted on said conduit and connected to said valve, said last named conduit having a head reservoir disposed above the boiler connecting point thereof.

6. In a feed water regulating system for a boiler, the combination of a diaphragm operated valve controlling the feed water line of the boiler, a pressure generator means attached to the boiler and connected to the valve to operate the same, a closed loop containing liquid having an end thereof connected to the boiler above the normal water level of the boiler and at its other end to the boiler nozzle and a plurality of pressure generator means mounted on the conduit and connected to said valve to operate the same in cooperation with said first named pressure generator means.

7. A feed water system for a boiler, comprising a feed water line, a valve adapted to continuously regulate the flow of feed water in said line, a pressure generator having a duct connected to the boiler to span the normal water level thereof, said pressure generator being connected to the valve to operate the same, a pressure regulating valve controlled by the boiler pressure and connected in the feed water line, means connecting the boiler to the pressure regulating valve whereby the latter will maintain a constant difference in the pressures between the feed water line and boiler, a looped conduit containing liquid connected to the boiler drum at one end and to the boiler outlet nozzle at its other end, and a pressure generator carried thereby, the pressure generator being associated with the first generator whereby the feed water valve may be operated consequent to variation in the difference of pressure being in the boiler and in the nozzle leading from the boiler while said pressure reducing valve maintains the pressure of the feed water at the feed water regulating valve at a constant excess over the boiler pressure.

8. A feed water system for a boiler, comprising a feed water line, a diaphragm operated valve to continuously regulate the flow of feed water in said line, a pressure generator connected to the boiler to span the normal water level thereof, said pressure generator being connected to the diaphragm of the valve to operate the same, a pressure regulating valve connected in the feed water line of the regulating valve on the remote side relative to the boiler, means connecting the boiler to the pressure regulating valve whereby the latter may maintain a constant difference in the pressure of the feed water line and boiler, a manometer containing liquid connected to the boiler drum at one end and to the boiler outlet at its other end, a pressure generator mounted on the manometer whereby generator pressures are responsive to variations in the difference in steam pres-

sure within the drum and boiler outlet, said last named pressure generator being connected to the first generator whereby the feed water valve may be operated simultaneously or non-simultaneously by changes in steam flow from the boiler and by variations in the boiler water level.

9. In a feed water system of the character described, the combination of a manometer tube containing liquid connected to the drum and outlet nozzle of the boiler, a pressure generator mounted on the tube, a diaphragm operated valve, a feed water line for the boiler controlled by the valve, and a conduit connecting the generator to the diaphragm valve whereby the feed water regulating may be controlled by variations in the steam flow from the boiler.

10. The method of varying the feed water flow to a boiler which includes the generating of feed water valve operating pressure in a circuit which is dependent upon changes in the water level in the boiler and supplementing this varying pressure with further variations in pressure which correspond to variations in the rate of steam flow from the boiler while maintaining the feed water pressure at a constant excess over the varying boiler pressure.

11. In combination, a boiler, a manometer loop containing liquid connected to a nozzle of the boiler at one end and to the upper steam zone part of the boiler at its other end, a pressure generator mounted on the loop and adapted to control means for regulating the thermal conditions of the boiler.

12. In combination a boiler, a manometer loop containing liquid, one end of the loop being connected to one part of the system containing steam, the other end to another part of the system containing steam, between which parts a difference in steam pressure is created dependent upon the load on the boiler and pressure generator means mounted on the loop and adapted to control means for regulating the feed water flow to the boiler.

13. The method of operating a pressure actuated feed water valve involving the creation of a common fluid pressure from two independent pressure sources including the steps of creating a valve actuating pressure in response to variation in boiler water level, creating another valve actuating pressure in response to variation of boiler load, and combining and exerting the combined pressure to actuate the said feed water regulating valve.

14. In a boiler feed water system, a feed water pipe, a pressure actuated valve in said pipe, a pressure chamber associated with said valve, pressure generator means responsive to change in boiler water level and connected to said chamber, and pressure generator means responsive to change in boiler load connected to said chamber.

15. The method according to claim 13 car-

ried on while controlling the fluid pressure drop across the feed water valve.

16. The system according to claim 14 including means for controlling the fluid pressure drop across said valve.

17. The method of operating pressure actuated feed water valve means involving the creation of fluid pressure from two independent sources including the steps of creating a valve actuating pressure varying in response to changes in boiler water level, creating another valve actuating pressure in varying response to changes in boiler load, and exerting the pressures so generated to actuate said feed water valve means.

In testimony whereof, I hereunto affix my signature.
